(57) **CLAIM**

The ornamental design for a pill dispenser, as shown and described.

DESCRIPTION

FIG. 1 is a top front right side perspective view of a pill dispenser, shown in use with environment;

FIG. 2 is a top front right side perspective view of the pill dispenser;

FIG. 3 is a bottom rear left side perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines depict portions of the article and environment that form no part of the claimed design.

1 Claim, 9 Drawing Sheets
